(57) **CLAIM**

The ornamental design for a terminal socket, as shown and described.

DESCRIPTION

FIG. 1 is a front view of a terminal socket showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a left side view thereof, in a condition wherein a release lever is pulled down;

FIG. 8 is a perspective view thereof; and,

FIG. 9 is a exploded perspective view of a release lever thereof.

The claimed design is embodied in the appearance of the socket as it seen in FIGS. 1-8. The release lever is shown separately in FIG. 9 in order to disclose aspects of the design that are not apparent from the other views.
